1,923,329

SAND MIXER FOR SAND BLAST MACHINES

Richard Ruemelin, Milwaukee, Wis.

Application June 24, 1929. Serial No. 373,154

4 Claims. (Cl. 51—12)

My invention relates to a sand mixer box for sand blast machines for regulating the flow of sand from the supply tank to the mixer chamber. A primary feature resides in providing means for regulating the flow of sand by a flexible member which depends virtually straight from the sand tank and wherein means operate on the flexible tubular member to flatten the same to decrease to the point of cutting off the flow of sand and to regulate the flow by the degree of flattening of the flexible member.

A feature of my sand mixer resides in a mixing box having a casing with a cover member which may be readily removed without disturbing the inner parts or for replacement of the same and to expose the parts within the mixing box when the cover is removed.

It is also a feature of my sand mixer box to provide lever operating means which are adapted to operate the vise-like pinching members for flattening the tubular flexible member and in means for holding the lever in a set position so that the flow of the sand may be regulated and maintained at a set pre-determined flow into the mixing box.

In this mixer box I provide means of causing the sand to flow from the supply tank into the mixer box in a conical or pyramidal formation of the sand which is directly in the path of the compressed air passing to the sand blasting nozzle. The structure of my sand mixer box is such that compressed air may also flow to the blasting nozzle by passing around the sand cone, which condition is particularly prevalent at the time when a large sand cone is formed in the mixer box, such as would take place when the compressed air is shut off for a time through the mixer box. This permits the mixer to pick up the sand and carry it off around the cone and eventually directly through the cone at the start of the flow of air through the mixer after it has been shut off and the sand flow permit it to remain at a set flow.

These features together with other details and objects of the invention will be more fully and clearly set forth in the specification and claims.

In the drawing forming part of this specification:

Figure 1 illustrates a detail of my mixer box for sand blast machines, showing the cover of the same removed, illustrating in section a portion of the supply tank and also the operating lever.

Figure 2 is a section on the line 2—2 of Figure

1, showing the flexible sand feeder in the mixing box closed.

Figure 3 is a similar section to Figure 2, showing the flexible sand feeder open.

I have illustrated in the drawing my sand mixer box A which is attached by the pipe 10 to the sand tank B.

The sand mixer box A is formed with a casing portion 11 having a flange 12 to which the cover 13 is secured by suitable bolts extending through the openings 14 in the cover and flange 12.

The sand mixer box A is supported by the pipe 10 directly below the sand supply tank B and in a manner so that the sand can flow from the tank B into the mixing chamber 15 of the sand mixer box A. Extending from the pipe 10 I provide a nipple 16 within the mixer A which is adapted to support the flexible sand feeder or hose 17 with the free end 18 of the sand feeder depending into the chamber 15 in the lower portion of the mixer box A.

The casing 11 of my sand mixer box A is formed with an inwardly projecting shoulder portion 19 on one side which extends closely adjacent the side of and near the free end 18 of the flexible sand feeder 17. On the opposite side to the shoulder 19 I provide a lever 20 formed with an engaging lug 21 which is adapted to be positioned as illustrated in Figure 3, in a manner so that when the lever 20 is operated the lug 21 will pinch the free end 18 of the flexible sand feeder 17 against the inwardly projecting lug 19 and tend to close the flexible sand feeder 17, as illustrated in Figure 2. The operation of the lever 20 will partially close or completely close off the flexible sand feeder 17 and stop the flow of sand into the mixer A.

The lever 20 is adapted to be operated by the shaft 22 which is rotated by the lever 23 secured to the outer end of the same and by means of the friction knob 24 which is threaded in the upper end 25 of the lever 23 a frictional contact can be made at 26 with the quadrant member 27 which is fixedly secured in a manner so that the lever 23 can be set to position the lever 20 in the sand mixer A in the desired position, either to shut off the sand flowing from the supply tank B into the mixer A, or to partially close the sand feeder 17 or to open it wide and permit the sand to flow freely into the mixing chamber 15 of the mixer A.

The compressed air is passed through the mixing chamber 15 by the inlet 28 and the outlet 29. The outlet 29 leads through the hose 30 to the blasting nozzle 31.

In the use of my sand mixer A compressed air is passed through the mixing chamber 15 and the flexible sand feeder is set by the pinching means to cause the correct amount of sand to flow into the mixing chamber 15. It is apparent that the flow of sand can be very easily regulated by properly setting the operating lever 23 which regulates the lever 20 and causes the lug 21 to pinch the flexible sand feeder 17 more or less as may be desired. It sometimes becomes necessary to shut off the sand blast and this is usually done by shutting off the compressed air, leaving the flow of sand set to flow into the mixing chamber 15. This permits the shutting off of the sand blast without changing the flow of the mixture of the sand and thus keeps the mixture of sand and air the same throughout the entire work of sand blasting in a particular operation. This is very important because after the sand has been set to flow in the operation of a particular piece of sand blasting work it is essential that the mixture be not changed until the work is completed. I am able to accomplish these results very readily with my sand mixer A.

Another feature of the invention which is important resides in the simplicity of structure. The feeder may be pinched readily to any degree and to close off the same and a very strong and substantial hose or flexible sand feeder member 17 may be provided having long wearing qualities and being highly resistant to the action of the air and sand past the same which is very important.

It is also apparent that when the air is shut off that the sand will build up into a conical formation as illustrated in Figure 2 below the free end of the hose 17 and if the hose is open slightly or partially the flow of sand will stop after the cone is built up to the end of the hose or feeder. When the compressed air is again turned on it will pass over and around the cone of sand, such as C, until the sand cone is diminished to a certain extent and then the air blast will pass directly through the passageway 15 carrying the flow of sand from the feeder 17 through to the nozzle 31. It is readily apparent that the removal of the cover 13 may be easily accomplished and the inner parts adjusted or changed in the sand mixer A. The advantages of my mixer are quite apparent and I have found the same to be very desirable in use in the mixing of sand blasting.

In accordance with the patent statutes I have described the principles of my sand mixer for sand blast generators and while I have illustrated and described a particular formation and operation of the parts, I desire to have it understood that the same is only suggestive of a means of carrying out the principles of my invention and that obvious changes may be made within the scope of the following claims without departing from the purpose and intent thereof.

I claim:

1. A sand mixer for sand blast machines including, a casing, a removable cover extending across one side of said casing, a nipple projecting into said casing, a flexible tubular member secured to said nipple and having a free open end extending therefrom, lever means and shoulder means for pinching the free end of said flexible member closed, said nipple and flexible member being connected with a source of supply of blasting sand, and an air chamber into which the free end of said flexible member depends adapted to be connected with a source of compressed air and having an outlet therefrom. 80

2. A sand mixer for sand blast machines including, a casing, a chamber formed in said casing, a flexible tube extending in said chamber connected on one end with said casing and to a source of supply of blasting sand, the other end of said flexible member being freely disposed and depending through said chamber, an air chamber formed below said first chamber having a horizontal inlet and outlet passageway to permit air to be passed under pressure therethrough, and means for pinching the free end of said flexible member 90 closed to shut off the source of supply of blasting sand to said air chamber in a manner to form a cone-shaped pile of blasting sand in said air chamber extending with its apex from the free end of said flexible member. 95

3. A sand and air mixer for sand blasting equipment including, a casing, means for connecting said casing with a source of supply of blasting sand, a chamber formed in said casing, a flexible tube depending from the top of said chamber 100 with one end secured in a manner to connect with the source of supply of sand and the other end freely disposed in said chamber, means for pinching the free end of said flexible member closed to shut off the same, and an air chamber 110 formed below said flexible member and into which it is adapted to project, said air chamber having a connection with a virtually horizontally extending source of compressed air and an outlet to a sand blasting nozzle and providing a 120 chamber wherein a conical-like pile of sand is formed with a free passage of air around the sand when the free end of said flexible member is partially and entirely closed. 115

4. A sand and air mixer including, a casing, 125 an upper chamber formed in said casing, a lower chamber formed below said upper chamber, a flexible sand shut-off extending through said upper chamber from a source of supply of sand and having its free end depending into said 130 lower chamber, said lower chamber providing an air inlet and outlet means extending angularly in relation to said flexible member, and means for pinching the free end of said flexible member to open and close the same. 135
